US00D816476S

(12) **United States Design Patent** (10) **Patent No.:** **US D816,476 S**
Shargh (45) **Date of Patent:** **** May 1, 2018**

(54) **TARP CLIP**

(71) Applicant: **HAMPTON PRODUCTS INTERNATIONAL CORPORATION**,
 Foothill Ranch, CA (US)

(72) Inventor: **Hossein Molaie Shargh**, Santa
 Margarita, CA (US)

(73) Assignee: **HAMPTON PRODUCTS INTERNATIONAL CORPORATION**,
 Foothill Ranch, CA (US)

(**) Term: **15 Years**

(21) Appl. No.: **29/599,673**

(22) Filed: **Apr. 5, 2017**

(51) LOC (11) Cl. **08-08**
 (52) U.S. Cl. **D8/395**
 USPC **D8/395**

(58) **Field of Classification Search**

USPC D8/349, 382, 394, 395, 398; D23/367;
 D26/125
 CPC A47G 25/485; B65D 33/16175; D06F
 55/02; F16B 2/10; F16B 2/20
